UNITED STATES PATENT OFFICE.

HAROLD A. WILLS, OF PLAINFIELD, NEW JERSEY.

RAILROAD CROSSTIE.

Application filed August 14, 1926. Serial No. 129,164.

The invention relates to an improvement in railroad cross ties. If wood were as durable and as wear-resistant as reinforced concrete it would make a satisfactory railroad cross tie (except for anchorage); because it possesses the requisite resiliency and the cohesion of its fibres is such as to properly retain the spikes for a reasonable length of time. But wood suitable for railroad cross ties is becoming scarcer all the time and correspondingly expensive. Accordingly, efforts have been made to employ substitute substances, especially reinforced concrete. Concrete used alone as a solid cross tie is impractical because it does not possess the necessary resiliency. Moreover, the stone-like nature of concrete prevents the use of ordinary spikes for holding the rails. For these and other reasons concrete cross ties unless combined with more or less expensive metal appliances are not used. The usual type of reinforced concrete cross ties proposed as a substitute for wood cross ties comprises two concrete end blocks each located under a rail and connected together by metal bars or strips so arranged as to afford a flexible connection between the two concrete blocks. The purpose of this flexible metal connection between the concrete bearing blocks is to permit each block to respond to the load conditions on its track without affecting the other block. This construction has not proved entirely satisfactory. The steel or iron of which these parts are usually constructed readily rusts, thereby preventing relative movement between the parts supposed to yield or hinge on each other, with consequent damaging results to the concrete, which breaks or cracks under the stresses imposed on it by the rigid connecting metal. Even where the flexible metal connecting does not rust, it is unsatisfactory because it permits the concrete blocks to tip relatively to each other and destroy the gauge of the track.

The general object of the present invention is to produce an improved railroad cross tie of such construction that it will possess all the advantages of an all wood tie, with the additional advantage possessed by reinforced concrete. A more specific object of the invention is to produce a railroad cross

tie of concrete bearing blocks so connected as to afford the proper amount of relative movement between them without imposing a cracking or breaking strain upon them, and without permitting them to move far enough to destroy the gauge of the track. Another object of the invention is to simplify the construction of railroad cross ties of this type so that they may be kept in effective operation with less labor and inspection than is required for keeping either the all wood ties, or the combination metal-concrete ties, as heretofore constructed, in effective condition. A still further object of the invention is to construct the rail supporting part of the cross tie in such manner that the wear or thrust blocks or parts may be readily replaced and at a minimum of cost both for labor and for the parts replaced. To these ends the invention consists in the improved railroad cross tie hereinafter fully described and particularly pointed out in the appended claims.

In the accompanying drawings illustrating the preferred form of the invention, Fig. 1 is a longitudinal section through the improved railroad cross tie taken along the line 1—1 of Fig. 2, with certain parts shown in side elevation; Fig. 2 is a top plan of the parts shown in Fig. 1; Fig. 3 is a side elevation of one of the reinforced concrete blocks or bases and its associated parts; Fig. 4 is a transverse section taken along the line 4—4 of Fig. 2; Fig. 5 is a side elevation of a modified form of the improved railroad cross tie; Fig. 6 is a view similar to Fig. 5, but with the concrete blocks shown in longitudinal section; Fig. 7 is a top plan of the modified form of the invention of Figs. 5 and 6, showing extra wide concrete blocks having two connecting pieces; Fig. 8 is a side elevation, partly in section, of another modified form of the invention; Fig. 9 is a top plan of a form of the invention shown in Fig. 8, the concrete blocks being wide enough to support three tie plates; Fig. 10 is a section taken along the line 10—10 of Fig. 9; Fig. 11 is a section taken along the line 11—11 of Fig. 9; Fig. 12 is a side elevation, partly in section of another modified form of the invention; and Fig. 13 is a top plan of the cross tie shown in Fig. 12. The improved railroad cross tie illustrated

in Figs. 1 to 4, showing the preferred form of the invention, comprises two reinforced concrete blocks or bases 15 and 16 adapted to be located under the rails 17 and 18, respectively. In order to afford the proper support for the rails 17 and 18 the concrete blocks 15 and 16 are much wider and are deeper than the average all wood tie, and are of such length that when the ballast 10 of the road bed is tamped beneath them there is a solid bearing of sufficient extent on each lateral side of the rail center. Thus there is afforded for the rail a greater bearing area than is afforded by the average all wood tie, because in the case of the latter, which is only usually eight or nine inches wide, it has been found practicable to tamp the ballast only from fifteen to eighteen inches on each side of the rail. To prevent the ballast from spreading and working out from under the concrete blocks, the edges of the bottom surfaces of the latter are provided with a peripheral downwardly extending flange 20 by which the material 20 of the road bed is prevented from working out in any direction from the recessed bottoms 21 of the concrete blocks.

The concrete blocks 15 and 16 are held together to constitute the end portions of a single cross tie by means of a wood connecting piece 23. The connecting piece 23 is in all respects like the usual all wood cross tie, except that it is much smaller in cross-section and is not so long as the all wood tie, projecting only a short distance at each end beyond the rails 17 and 18, as shown in Fig. 1. This all wood connecting piece for the concrete blocks permits them to have that movement relatively to each other under the varying load conditions to which they are subjected without imposing a breaking or cracking strain upon them. Moreover, the use of this all wood connecting piece affords the same facility for fastening the rails 45 to the cross tie as is afforded by the usual all wood cross tie.

The connecting piece 23 is received at its ends within the recessed inner facing ends 24 and 25 of the blocks 15 and 16. 50 The connecting piece 23 being substantially rectangular in cross-section, the recesses 26 in the concrete blocks are substantially rectangular in cross-section and extend outwardly into the blocks far enough to accommodate the bolts 27 by which the ends of the connecting piece are secured in the outer ends of the concrete blocks. The recesses are sunk deep enough into the concrete blocks to bury the upper surface 28 of 60 the connecting piece below the upper surface 29 of the concrete blocks so as to provide space for a wear piece or block 30 composed of wood and superposed upon each end of the connecting piece 23. The wear pieces 30 are sunk fully half their

depth in the upper part of the recesses 26 and are prevented from spreading laterally under the load imposed on the rails by means of the upper lateral sides of the concrete blocks bounding the recesses 26. The outer 70 ends 32 of each concrete block extend upwardly to act as thrust surfaces for the outer ends of the connecting piece 23 and of the wear pieces 30. The upper surfaces of the outer ends 32 of the concrete blocks 75 are substantially flush with the upper surfaces of the wear pieces 30. The outer bolts 27 and the inner bolts 33 holding the wear pieces against the outer ends of the connecting piece 23 and the latter in 80 position in the concrete blocks pass through alined holes in the wear pieces and the connecting piece and are threaded at their lower ends into the nuts 34 embedded in the bottoms of the concrete blocks. Bushings 35 85 which may be composed of sections of pipe may be conveniently embedded in the concrete blocks above the nuts 34 to form holes alining with the holes in the wear pieces 30 and the connecting piece 23. Since there is 90 no direct pressure of the load upon that portion of the wear pieces and the connecting piece through which the bolts 27 and 33 penetrate there is no tendency of the bolts to shear and they remain tight, with only 95 occasional attention, throughout the life of the wear pieces 30.

The wear pieces 30 are relatively short in length, extending from the ends of the connecting piece 23 only to the inner ends of 100 the concrete blocks 15 and 16, or a little beyond, as shown in Figs. 1 and 2, and are only of the requisite thickness to withstand properly the thrust of the tie plates 37 under the action of the load imposed on the rails 17 and 18. The wear plates 37 are provided on the outer ends of their upper surfaces with the upraised lips 38 adapted to bear against the outer edges of the bases of the rails, and are provided 105 on their lower surfaces with the lateral downwardly extending flanges 39 which tightly embrace and hold the lateral edges of the wear pieces 30 and thereby prevent the latter from spreading under the action of 115 the load. Each tie plate 37 is provided with the four square holes 40 to accommodate the usual spikes 41 which are used to hold the bases 42 of the rails 17 and 18 in place on the tie plates. The spikes 41 are of usual 120 length and are driven into the wear pieces 30 and the ends of the connecting piece 33, as clearly indicated in Fig. 1. The combined thickness of the connecting piece 23 and wear pieces 30 is such that the lower 125 ends of the spikes 41, when the wear pieces 30 are new, are separated from the bottom of the recesses 26 a distance sufficient to permit the spikes to be driven deeper into the connecting piece 23 as the wear pieces 30 130

wear away under the action of the load on the rails.

The improved railroad cross tie described above will be seen to have all the advantages of an all wood cross tie as to resiliency and the means for holding the ordinary rail fasteners in place, combined with all the advantages afforded by reinforced concrete bearing blocks or bases. The railroad cross tie as thus constructed requires but little attention while in use, and that from only unskilled labor. When the wear pieces 30 become worn slightly under the action of the load on the rails, it is simply necessary to drive down the spikes 41 deeper into the connecting piece 23.

When the wear pieces 30 have become so badly worn that the lower ends of the spikes 41 touch the bottoms of the recesses 26 in the concrete blocks, unskilled labor can be availed of to replace the wear pieces, since it is only necessary to remove the spikes and the bolts 27 and 33 without disturbing the position of either concrete block, or the connecting piece 23, or the opposite wear piece. The renewal of the wear pieces will usually be effected without retamping the ballast under the concrete blocks, since the flanges on the latter hold the ballast in place. The worn out wear pieces 30 are moved inwardly from under the rails and the new wear pieces shoved into their place. These new wear pieces will be provided with holes alining with the holes in the ends of the connecting piece 23. The bolts 27 and 33 may thereupon be replaced and when the tie plates 37 have been placed under the bases of the rails it is simply necessary to drive in the spikes 41. It is thus seen that no skilled labor is required in reconditioning the cross tie of the present invention and that it can be done with far less cost for labor and material than it is possible to replace or recondition all wood ties.

In the form of the invention shown in Figs. 5, 6 and 7 the concrete blocks or bases 45 and 46 are wide enough to accommodate two connecting pieces 47. For some conditions of road surface it is desirable to use these double blocks rather than the single block shown in Figs. 1 and 2. For still other conditions of road surface it has been found desirable to use the extra wide concrete blocks 48 and 49, shown in Fig. 9, connected by two connecting pieces 50, providing space between them for a third tie plate 51.

In the form of the invention shown by Figs. 5, 6 and 7 the recesses 52 in the blocks 60 for the accommodation of the connecting pieces 47 extend throughout the length of the blocks, and the connecting pieces 47 extend from the outer end of one concrete block 45 to the outer end of the other concrete block 46. In this form of the invention

the wood connecting pieces are overlaid by a wood wear piece 53 substantially as done as each connecting piece, as shown in Figs. 5 and 6. The wear pieces 53 and connecting pieces 47 are provided with alining holes which register with the nuts 54 embedded in the bottoms of the concrete blocks and the parts are secured together by means of the bolts 55. The tie plates 56 for the rails occupy a position over the medial line 75 of the concrete blocks so that the load will be evenly distributed throughout their lower surfaces.

In the form of the invention shown in Figs. 8 and 9 the concrete blocks have substantially the same construction as the blocks shown in Fig. 7, except that space is provided at their middle portions for the third tie plate 51. In this form of the invention the tie plates 57 are made long enough to receive the bolts 58 which secure the wear pieces 59 and the connecting pieces 50 to the concrete blocks 48 and 49. The wear pieces 59 in this form of the invention extend from the ends of the connecting pieces 50 to the middle thereof and are joined to the connecting piece at this point by means of the plate 61. In this form of the invention when the outer ends of the wear pieces 59 become worn they can be removed and turned end for end, the former outer ends overlying the middle of the connecting pieces 50 and the former inner ends serving to support the tie plates 57. For this purpose each wear piece 59 is provided with the extra hole 62, which, with the hole through which the screw 61 passes, serves to accommodate the bolts 58 in the new position of the wear piece. Since the middle portions of the concrete blocks 48 and 49 are not joined by a connecting piece 50 it is only necessary to provide this part of the blocks with a relatively shallow recess to accommodate the relatively thin wear piece 64, which is only as long as the concrete blocks. To accommodate the lower ends of the spikes wood blocks 65 are embedded in the bottom of the recess 66.

In its general arrangement the form of the invention shown in Figs. 12 and 13 is similar to that shown in Figs. 5 and 6, except that in this case the outer ends 68 of the concrete blocks 69 and 70 extend upwardly to serve as thrust surfaces for the connecting piece 71. In this form of the invention, also, I prefer to use the elongated tie plates 72 which are held in place on the long wear piece 73 by means of the bolts 74 which secure the wear piece 73 and the connecting piece 71 to the concrete blocks 69 and 70. In order that the end of the connecting piece 71 and the wear piece 73 may not move laterally in the concrete blocks the latter are provided with the upwardly extending sides 75, which closely embrace the lateral sides of 130

the wood pieces. The middle portions of these upwardly extending sides 75 of the concrete blocks are recessed at 76 to accommodate the downwardly extending flanges 5 77 on the middle parts of the tie plates 72.

Having thus described the invention what I claim as new is:

1. A railroad cross tie comprising, two concrete blocks substantially rectangular in cross-section and having on their inner ends a substantially rectangular recess, a wood connecting piece substantially rectangular in cross-section mounted at its ends in the recesses in the concrete blocks and extending 10 from beyond one rail to beyond the other, the connecting piece being of less depth than the recesses in the concrete blocks, and a relatively short wood wear piece superposed on each end of the connecting piece, and 15 embraced laterally by the sides of the recesses in the concrete blocks, said wear pieces being located under the rails and being removably secured to the connecting piece.
2. A railroad cross tie comprising, two 20 concrete blocks recessed in their inner facing ends to receive the ends of a connecting piece, a wood connecting piece substantially smaller in cross-section than the concrete blocks and extending from beyond one rail to 25 beyond the other and supported at its ends in the recesses in the concrete blocks, the connecting piece being of less depth than the recesses in the blocks, a relatively short

wood wear piece superposed on each end of the connecting piece and located under the rails, means for removably securing the wear pieces and the connecting piece to the concrete blocks, a metal tie plate superposed on each wood wear piece to support the base of the rail, each tie plate being provided 30 with two lateral downwardly extending flanges embracing the sides of the wear pieces to prevent lateral spreading thereof, and means for securing the tie plates to the wear pieces and connecting piece. 45

3. A railroad cross tie comprising, two concrete blocks adapted to be located under the rails and having on their inner faces an elongated recess substantially rectangular in cross-section, a wood connecting piece 50 substantially rectangular in cross-section mounted at its ends in the recesses in the concrete blocks and extending from beyond one rail to beyond the other, a relatively short wood wear piece superposed 55 on each end of the connecting piece, the wear pieces, each connecting piece and the concrete blocks being provided on each side of the rail with a hole alining with the holes in the other parts, nuts embedded in the bottoms of the concrete blocks in alignment with the holes therein, and bolts for securing the wear pieces and the connecting piece to the concrete blocks, said bolts being threaded into the nuts in the concrete blocks. 60

HAROLD A. WILLS.
